UNITED STATES PATENT OFFICE.

JOSEPH P. LANE, OF NEW YORK, N. Y.

GAS STOVE.

Application filed April 5, 1923. Serial No. 630,149.

To all whom it may concern:

Be it known that I, JOSEPH P. LANE, a citizen of Russia, and a resident of the city of New York, borough of Manhattan, in the county and State of New York, have invented new and useful Improvements in Gas Stoves, of which the following is a full, clear, and exact description.

This invention relates to gas stoves primarily designed for use as heaters.

The object of the invention is the provision of a simply constructed gas stove provided with means for giving complete combustion of the gases so as to obtain great heating efficiency.

This object is accomplished by providing a gas distributing manifold having perforated areas in its top wall, mounting on said manifold and in alignment with the perforated areas a plurality of tubes forming combustion chambers, and forming in the walls of the tubes openings which control the length of the flame.

This and other objects of the invention will be more clearly understood from the following detailed description and accompanying drawings.

Figure 1 is a front elevation of the gas stove with a portion of the manifold and a tube cut away to show the construction;

Figure 2 is a horizontal section along the line 2—2, Figure 1;

Figure 3 is a vertical transverse section on the line 3—3, Figure 2, showing the construction of a tube and the manifold;

Figure 4 is a top elevation showing a perforated area provided in the top wall of the manifold.

Referring to the above-mentioned drawings, the invention includes a casing 10 in which a gas supply manifold 11 is mounted, extending horizontally across the bottom of the casing. A plurality of perforated areas 12 including perforations 17 are provided in the top wall of the manifold. Mounted on the manifold in alignment with the perforated areas 12 are a plurality of tubes 13 open at both ends. These tubes 13 are made with flanges 14 in order to facilitate their mounting on the manifold. A plate 15,

having a plurality of openings therein which fit over the tubes 13 engaging the flanges 14, is provided. This plate seats on the manifold and is tightly attached thereto by rivets 16 retaining the tubes 13 in their vertical positions. Each tube 13 has an opening 18 cut in its side at a predetermined distance from its base. In certain constructions each tube might be provided with a plurality of openings 18 and a sliding member for closing all the openings except the one it is desired to use. The gas is supplied to the stove through the pipe 19 provided with an opening 20 for permitting the intake of air for mixing with the gases to be burned.

The openings cut in the tubes 18 control the length of the flame. By increasing the distance that the openings 18 are spaced from the lower ends of the tubes 13 the length of the flame may be varied. Under fixed conditions there is a maximum length of flame for different gases, which gives the greatest burning efficiency and consequently the greatest heating efficiency. This has to be obtained by experiment and consequently the distance that the openings 18 would be spaced from the bottom of the tubes 13 would be decided upon after a generalization of a large number of experiments with different gases to arrive at the proper positioning of the openings in order to give the maximum efficiency for the various gases supplied by the different gas supply companies.

I would state in conclusion that while the illustrated example constitutes a practical embodiment of my invention I do not limit myself strictly to the exact details herein illustrated since manifestly the same can be considerably varied without departing from the spirit of the invention as defined in the appended claims.

Claims:

1. A gas stove, comprising a casing, a manifold mounted in the casing, said manifold having a plurality of perforated areas in its top wall, a plurality of tubes open at both ends mounted on said manifold in alignment with the perforated areas form-

ing combustion chambers, said tubes being provided with means for limiting the height of the flame when the stove is in operation.

2. A gas stove, comprising a casing, a manifold mounted in said casing, said manifold having a plurality of perforated areas in its top wall, and a plurality of tubes

for forming combustion chambers mounted on the manifold in alignment with said perforated areas, said tubes having openings cut in their walls for limiting the length of the flame. ¹⁰
